SEPARABLE BUTTON ATTACHING DEVICE

Arthur M. Ellis, Knoxville, Tenn.

Application February 14, 1950, Serial No. 144,075

2 Claims. (Cl. 24—107)

1

This invention relates to devices for attaching objects, such as buttons and ornaments, to fabrics, such as garment fabric, and more particularly to a separable fastening device for attaching a button or similar object to a garment so that the object can be attached and removed as desired.

It is among the objects of the invention to provide a separable fastener device for detachably securing an object, such as a button or ornament, to a garment which device includes a part that can be quickly and firmly attached to fabric and another part detachably secured to the first part and permanently secured to the object so that the object can be secured to and removed from the fabric as desired, which attaches the object to the fabric for freedom of tilting movement of the object relative to the fabric, and which is simple and durable in construction, easy to apply, and neat and attractive in appearance.

Other objects and advantages will become apparent from a consideration of the following description and the appended claims in conjunction with the accompanying drawing wherein;

Figure 1 is a top plan view of an attaching device illustrative of the invention;

Figure 2 is a side elevation of a portion of the attaching device;

Figure 3 is a cross sectional view on the line 3—3 of Figure 1;

Figure 4 is a medial cross section of a complete assembly including a separable attaching device, a button and a piece of fabric to which the button is detachably secured by the attaching device;

Figure 5 is a side elevation of one form of staple for connecting a button to the attaching device;

Figure 6 is a side or edge elevation of the staple illustrated in Figure 5;

Figure 7 is a side or edge elevation of a blank or forming a somewhat modified form of attaching staple;

Figure 8 is a top plan view of the staple illustrated in Figure 7;

Figure 9 is a front elevation of a staple formed from the blank illustrated in Figures 7 and 8;

Figure 10 is a bottom plan view of the staple illustrated in Figure 9;

Figure 11 is a transverse cross sectional view of a button showing one means of attaching the button to a staple;

Figure 12 is a cross sectional view similar to Figure 11 showing a different means for attaching the button to a somewhat modified form of staple;

2

Figure 13 is a cross sectional view similar to Figures 11 and 12 but for showing means for attaching the button to a still further modified form of staple;

Figure 14 is a side elevation of a button attaching assembly embodying the button attaching means illustrated in Figure 11;

Figure 15 is a front elevation of a still further modified form of button attaching staple;

Figure 16 is a side or edge elevation of the staple illustrated in Figure 15; and

Figure 17 is a side elevation of a somewhat modified form of button attaching device, a portion being broken away and shown in cross section to better illustrate the construction thereof.

With continued reference to the drawing and particularly to Figure 4, the complete assembly comprises, in general, a fabric piece 10 which may be a part of a garment, a hollow female member 11 set on the fabric piece, a washer 12 set on the side of the fabric opposite the female member 11 and having prongs or teeth extending through the fabric and engaging the female member to firmly and permanently attach the female member to the fabric, a hollow male member 13 detachably engaged in the female member 11, a staple 14 permanently engaged at one end in the male member 13 and an object 15, such as a button, having a formation with which the staple 14 is engaged.

The female member 11 and the washer 12 may be of well known or conventional construction. The female member is a disc or washer shaped member having a centrally disposed upstanding boss 16 provided with an aperture and formed to provide resilient tongs 17 surrounding the aperture, and a marginal beaded or turned flange 18. This member is conventionally formed of resilient cheap metal and may be plated or coated as desired to give it an ornamental appearance.

The washer 12 is a ring shaped member of thin metal having a large aperture and tongs or prongs 19 extending from the inner side of the aperture in the washer 12 to one side of the washer.

These tongs may be forced through the fabric 10 and engaged in the beaded over flange 18 of the female member to firmly and permanently attach the female member to the fabric.

The male member 13 is also preferably formed of a suitable sheet metal and comprises a disc shaped body portion 20 surrounded by a beaded over marginal flange 21 and having a central, cylindrical boss 22 extending to one side thereof and surrounding a central opening in the body portion 20. The end of the boss 22 is closed by

a domed end wall 23 and adjacent this end wall the boss 22 has a formation 24 providing an annular groove in the outer surface of the boss.

When the boss 22 of the male member is forced into the boss 16 of the female member, the tongs 17 of the female member engage in the groove in the outer surface of the boss of the male member and firmly connect the two members together.

When the male and female members are used to attach buttons to a garment this connection is preferably made so firm that it cannot be overcome without the use of a suitable separating tool so that there will be no danger of the buttons or objects being accidentally lost by unintentional separation of the two components of the separable fastener assembly.

The staple 14 may be formed from a suitable length of stiff wire and is bent intermediate its length to provide a rounded or circular loop or eye 25 and two legs 21 and 28 which are substantially parallel and coterminous. The legs are bent outwardly at their ends opposite the eye 25 to provide respectively two lugs 29 and 30 which engage behind the formation 24 in the male boss 22 to firmly lock the staple in the male member.

The button 15 is a disc shaped member having a marginal beaded over flange 31 and is provided near its center with two spaced apart apertures 32 and 33 through which the legs of the staple 14 may be passed so that the loop or eye 25 of the staple surrounds the bridge portion 34 of the button between the two openings or apertures 32 and 33. This construction permanently attaches the buttons to the staple 14 and through the staple to the male member 13 but provides freedom of tilting movement of the button relative to the male member and the staple so that the button can be easily manipulated.

The somewhat modified form of staple illustrated in Figures 5 and 6 and generally indicated at 14a is of the same construction as the staple 14 except that it is formed of a piece of wire stock of rectangular cross sectional shape. It has the same features, characterized by the letter "a" after the numeral, as has the staple 14 described above.

The staple illustrated in Figures 7, 8, 9 and 10 is formed from a straight bar or blank 35 the intermediate portion 36 of which has one flat side and one convexly rounded side. Enlargements or projections 37 and 38 are provided on the curved side of this blank at the respectively opposite ends thereof and each projection may have on its outer end a small detent 39. The blank 35 is bent to form the staple 14b in the same manner as that in which the wire lengths are bent to form 14 and 14a and when bent provides a staple having a substantially circular loop or eye 25b, and two parallel and coterminous legs 27b and 28b. Instead of the legs being bent outwardly at their ends to provide the lugs 29 and 30 however the two lateral projections 37 and 38 on the blank provide these projections, the blank being bent with its flat side inward so that the projections are on the outer sides of the legs and extend away from each other. When the staple 14b is inserted into the boss of the male member of the separable fastener the lugs provided by the extensions 37 and 38 engage behind the formation 24 of the boss and lock the staple in the boss. If the detents 39 are provided, these detents engage with the inner surface of the boss of the

male member and provide an additional safety factor against accidentally pulling the staple out of the male member.

In the modified form of staple illustrated in Figures 15 and 16 and generally designated at 14c, the projections 37 and 38 are modified to a hemispherical form and these modified projections 40 and 41 provide a ball end on the staple which, when engaged behind the formation 24 in the boss of the male member of the separable fastener provide a limited universal movement of the staple in the male member boss to give a somewhat greater freedom of movement to the button or other object.

15 In Figure 11 there is illustrated a suitable formation for attaching a button to any one of the described staples. In this arrangement the button 15b is formed of a suitable moldable material, such as hard rubber or synthetic resin 20 plastic and a small metal ring 42 is set into the button so that approximately one-half of the ring projects outwardly of the button adjacent the center of the underside of the button. Before the staple is engaged in the boss of the male member of the separable fastener one of the staple legs is passed through the ring 42 so that the ring is engaged in the eye or loop of the staple.

16 In Figure 12 the button 15c may be formed of the same type of material as the button 15b. 30 In this case however the button is rigidly secured to the outer end of a staple or tongue 14d having one end engaged in the boss of the male member of the separable fastener and having at its outer end a cross bar 43 embedded in the 35 material of the button to firmly and permanently attach the staple or tongue to the button.

17 In Figure 13 the button 15d may also be of the same material or of the same general shape as the buttons illustrated in Figures 11 and 12.

40 In this case the staple or tongue 14e has one end secured in the boss of the male member of the separable fastener in the manner indicated above and has on its opposite end a ball formation 44 embedded in the material of the button substantially at the center of the button to firmly 45 attach the button to the staple or tongue.

18 Figure 14 illustrates a complete assembly utilizing the button 15b and the staple engaging formation 42 illustrated in Figure 11.

19 Figure 17 illustrates an arrangement which is modified to provide a lengthened boss 22a for the male member 13a so that the female member 11 may be set under a piece of fabric 45, which may constitute a hem or flap, and the boss of the male member engaged in the boss of the female member through an opening 46 provided in the extra piece of fabric 45 interposed between the male and female members of the separable fastener.

20 The invention may be embodied in other specific forms without departing from the spirit or essential characteristics thereof. The present embodiment is therefore to be considered in all respects as illustrative and not restrictive, the scope of the invention being indicated by the appended claims rather than by the foregoing description, and all changes which come within the meaning and range of equivalency of the claims are therefore intended to be embraced therein.

21 What is claimed is:

22 1. Means for detachably connecting a button to a piece of fabric having a female snap member secured thereon comprising a male snap member having a hollow boss adapted to be releasably

engaged in a complementary female member, said boss having an external annular groove and an internal annular formation intermediate its length, and a U-shaped staple adapted to extend at its closed end through the thread apertures in a button and being disposed at its open end in the boss of said male member with the end portions of its legs at the open end thereof divergently directed and engaged under said internal annular formation in said boss.

2. Means for detachably connecting a button to a piece of fabric having a female snap member secured thereon comprising a male snap member having a hollow boss adapted to be releasably engaged in a complementary female member, said boss having an external annular groove and an internal annular formation intermediate its length, and a U-shaped staple having at its closed end an eye formation of substantially

5 circular shape adapted to extend through the thread apertures in a button and being disposed at its open end in the boss of said male member with the end portions of its legs at the open end thereof divergently directed and engaged under said internal annular formation in said boss.

ARTHUR M. ELLIS.
